UNITED STATES PATENT OFFICE.

EDGAR E. BROSIUS, OF PITTSBURGH, PENNSYLVANIA.

CHARGING APPARATUS FOR ANNEALING-FURNACES.

1,389,238.

Specification of Letters Patent. Patented Aug. 30, 1921.

Application filed February 2, 1920. Serial No. 355,890.

To all whom it may concern:

Be it known that I, EDGAR E. BROSIUS, a citizen of the United States, residing at Pittsburgh, Allegheny county, Pennsylvania, have invented a new and useful Improvement in Charging Apparatus for Annealing-Furnaces, of which the following is a full, clear, and exact description, reference being had to the accompanying drawings, 10 forming part of this specification, in which:—

Figure 1 is a view partly in side elevation and partly in vertical section of one form of apparatus embodying my invention.

15 Fig. 2 is a plan view of certain of the parts shown in Fig. 1.

Fig. 3 is a plan view of the rake and its supporting and operating parts.

20 Fig. 4 is a longitudinal section of the apparatus shown in Fig. 3.

Fig. 5 is a longitudinal section on a larger scale of a portion of such apparatus, and

25 Figs. 6 and 7 are respectively plan and side views showing a modification of a portion of the apparatus.

30 My invention has relation to charging apparatus for annealing furnaces; and more particularly to apparatus of this character for use in connection with pipe annealing furnaces. In this class of furnaces the articles to be annealed, usually pieces of tool steel, are placed in large pipes which act as the containers therefor during the annealing operations. These pipes, with their charges, 35 are introduced into the furnace where they lie side by side; and after a certain period of heat treatment, it is necessary to turn the pipes 180° in order to more thoroughly equalize the heat treatment.

40 My invention is designed to provide apparatus of simple, convenient and efficient character, by means of which the loaded pipes may be charged into the furnace, may be rotated within the furnace when necessary, 45 and finally removed from the furnace. The invention provides means whereby these operations may be accomplished with a minimum amount of hand labor, and without necessitating exposure on the part of the operator to the intense heat of the furnaces. The operation, as heretofore performed by hand labor, has been an arduous one owing to the necessity, especially in turning the pipes, of the men getting close to the open doors of 50 the highly heated furnaces.

My invention also provides means in connection with the charging apparatus for elevating the loaded pipes to the level of the charging doors of the furnace and also for lowering the pipes to the floor level after the 60 completion of the annealing.

The nature of my invention will be best understood by reference to the accompanying drawings in which I have shown a preferred embodiment thereof and which will now be 65 described, it being premised, however, that various changes can be made in the details of construction, operation and arrangement of the various parts without departing from the spirit and scope of my invention, as defined in the appended claims.

In these drawings, the numeral 2 designates a rake adapted for introduction within the annealing furnace, and consisting of a transversely disposed bar having a plurality 75 of projecting teeth or fingers 3 adapted for engagement with the pipes. The bar 2 is carried by a longitudinal rack bar 4 which extends through the tubular frame or housing 5, its rear end portion having an elongated screw thread 6, as best shown in Fig. 5. This threaded portion of the rack bar extends within a sleeve 7 to the rear end of which is secured a hand operating wheel 8. In the opposite or inner end portion of the 85 sleeve 7 is a bushing member 9 formed with an internal thread adapted to the thread of the bar 2 and acting as a nut therefor. The sleeve 7 is rotatably mounted within the housing 5 on any suitable bearings, such as 90 the ball-bearings shown at 10.

The apparatus just described is designed, when in use, to be suspended from an overhead carrier. This preferably consists of a trolley 11 mounted on the traveling crane 95 bridge 12. The device is suspended at the point 13 by a chain 14 connected to the hook 15 of a pulley block 16 suspended from the hoisting drum on the trolley. It also has a rear suspension chain 17 which is connected to an extension 18 of the trolley. 19 designates a counterweight which is attached to the suspension member 20 to which the chain 17 is attached. This weight is shown as having a depending stop projection 21 adapted 100 to coöperate with the fixed floor stops 22 and 23. 24 designates a pawl pivoted to the suspension member 20 at 25 and adapted to be moved into and out of engagement 105 with a notch 26 (see Fig. 5) in the portion 5^a 110

of the housing 5. The purpose of this pawl is normally to prevent any tendency of the housing to rotate when the hand wheel 8 is turned.

5 27 designates a ring member which is secured to the sleeve 7, and which is provided with a seat for a stud bolt 28 or other similar device which may be turned to cause its inner end to engage with an opening 29 in 10 the housing member 5^a, for the purpose hereinafter described.

15 30 designates supports which form an elevating table for the pipes. These supports are carried on the plungers of power cylinders 31 as shown in Figs. 1 and 2.

The operation is as follows:

20 The pipes to be charged are placed upon the table in the manner shown in dotted lines in Fig. 1, the table being raised to the level of the charging door of the annealing furnace 32 as shown in said figure. The trolley 11 is then manipulated to cause the 25 rake to be engaged successively with the pipes and roll them into the furnace. After the pipes have been in the furnace the proper length of time, the rake is introduced 30 into the furnace in position to engage the first pipe which is then in the dotted line position indicated in Fig. 1. The suspending cable for the block 16 is slightly lowered so as to tilt the rake into a more effective 35 position. The hand wheel 8 is then actuated to pull the rake backwardly sufficient to rotate the pipe 180°, or to the full line position indicated for the first pipe in Fig. 1. The operation is then repeated for the 40 second pipe. While these operations are going on, the stop member 21 is coöperating with the fixed floor stop 23 to prevent undue movement of the rake on its suspensions. The trolley is then manipulated to bring the 45 parts in the full line positions shown in Fig. 1 in which the rake can be moved by the hand wheel to positions to successively engage and rotate the remaining pipes in the furnace.

50 At the conclusion of the annealing operations the rake is manipulated by means of the trolley to successively engage the pipes and roll them out of the furnace onto the table which may then be lowered. The annealed pipes are then removed, covered over and left to cool. A fresh charge of pipes is then placed on top of the cover and rolled 55 into the furnace by the charging machine. Before this new charge is ready to come out of the furnace, the other pipes are cooled and removed.

60 In some cases, as when the rake teeth become unduly bent, it may be necessary to slightly manipulate the rake in order to enable it to be introduced through the door of the furnace. If this occurs, the pawl 24 is thrown out of engagement and the stud bolt 28 turned to engage the aperture 29 in

the housing member 5^a. In this manner the rack bar carrying the rake is locked to the housing, and the entire device may be manipulated on the roller bearing suspensions by the hand wheel. The crane bridge 12 70 may be the usual overhead crane bridge employed in a mill of this character, the only change required being to provide the trolley with an extension of a suitable character to carry the suspension 17. During the intervals when the rake is not in use, the suspension chains 14 and 17 may be disconnected, leaving the overhead crane free for other uses about the mill. If the extension 18 is of rigid character, this might interfere with 75 some of these other operations, since it would prevent the crane trolley from being moved to the extreme right hand end of the crane bridge. To overcome this difficulty, I may use the construction shown in Figs. 6 and 7 80 85 in which such extension is shown as consisting of two members 33 and 34 connected by the hinge or pivot pin 35. The member 33 extends beyond the pivot pin 35 and engages the member 34 to prevent any further downward movement of said members beyond the position shown in Fig. 7. When, however, the trolley is run to a point sufficiently near the right hand end of the bridge 12 to cause the wheel 36 on said extension to engage the usual stop 37, the members 33 and 34 will readily buckle upwardly on the pivot 35, and thus permit the crane to be run up near 90 this end of the bridge. 95

The advantages of my invention will be 100 understood by those familiar with the present methods of charging annealing furnaces, since it reduces hand labor to a minimum; renders unnecessary exposure of the workmen to the heat of the furnaces; and provides simple, convenient and effective means 105 for handling and manipulating loaded pipes.

I claim:

1. The combination with a pipe-annealing furnace having a charging opening and a 110 hearth extending from said opening and forming a roll-way for the pipes, of a combined charging, manipulating and discharging device comprising a rake movable through said opening and over said roll-way, 115 a movable overhead support from which the said device is flexibly suspended, and stop means for limiting the movement of said device on its suspension in different positions of the overhead support, substantially as 120 described.

2. The combination with a pipe-annealing furnace having a charging opening and a hearth extending from said opening and forming a roll-way for the pipes, and a 125 loading and unloading table in front of said opening and having means for raising and lowering it, of a combined charging, manipulating and discharging device comprising a rake movable through said open- 130

ing and over said roll-way, and also over said table, and a movable overhead support from which said device is flexibly suspended, substantially as described.

- 5 3. The combination with a pipe-annealing furnace having a charging opening and a hearth extending from said opening and forming a roll-way for the pipes, and a loading and unloading table in front of said 10 opening and having means for raising and lowering it, of a combined charging, manipulating and discharging device comprising a rake movable through said opening and over said roll-way, and also over said 15 table, and a movable overhead support from which said device is flexibly suspended, together with a stop means for limiting the movement of said device when the rake is

over the hearth and also when it is over the table, substantially as described. 20

4. In apparatus for charging and manipulating pipe annealing furnaces, the combination with a combined charging and manipulating device, of an overhead trolley, said trolley having a hoisting drum, a flexible suspension connection between said drum and said apparatus, the trolley also having a rearward extension and another suspension connection between said extension and the said apparatus, and means 25 for permitting said extension to fold or buckle, substantially as described.

In testimony whereof I have hereunto set my hand.

EDGAR E. BROSIUS.
